ATTORNEY

UNITED STATES PATENT OFFICE.

JOHN RAYMAN JENNINGS, OF WEST NEWTON, PENNSYLVANIA.

RAIL-CHAIR.

1,079,768.

Specification of Letters Patent.

Patented Nov. 25, 1913.

Application filed August 5, 1913. Serial No. 783,146.

To all whom it may concern:

Be it known that I, JOHN RAYMAN JENNINGS, a citizen of the United States of America, residing at West Newton, in the county of Westmoreland and State of Pennsylvania, have invented certain new and useful Improvements in Rail-Chairs, of which the following is a specification, reference being had therein to the accompanying drawing.

This invention relates to rail chairs, and the objects of my invention are to provide a chair that can be easily and quickly mounted upon a tie or other support for positively holding a rail, and to furnish the chair with novel means, as hereinafter set forth whereby it cannot creep or shift relatively to the tie or support upon which it is placed.

Other objects of my invention are to provide a rail chair for rails wherein the rails have provision for preventing lateral displacement of the same upon the chair, and to provide a chair that can be used in connection with the present type of wooden ties to prevent the same from being unduly worn or agitated by rails mounted thereon.

Further objects of my invention are to provide a rail chair that can be easily and quickly manufactured and installed without the use of skilled labor, and to accomplish the above results by a durable structure that is applicable to various types of railways.

With the above and other objects in view the invention resides in the novel construction, combination and arrangement of parts to be hereinafter specifically described and then claimed.

Reference will now be had to the drawing, wherein:

Figure 1 is a side elevation of a chair in accordance with this invention. Fig. 2 is a top plan of the same, Fig. 3 is a side elevation of a portion of a rail adapted to be mounted upon the chair, Fig. 4 is a bottom plan of the chair, Fig. 5 is a bottom plan of the portion of rail illustrated in Fig. 3, Fig. 6 is a longitudinal sectional view of the rail chair, and Fig. 7 is a cross sectional view of the same.

A rail chair in accordance with this invention comprises a rectangular plate 1 and the bottom of said plate is provided with

longitudinally converging ribs 2 that are 55 V-shaped in cross section and are adapted to engage in the top of a wooden tie or other support. The ribs 2 converge from one end of the plate to the opposite end thereof and with said ribs V-shaped in cross section the 60 plate can be easily anchored upon a wooden tie.

The top of the plate 1 is provided with transverse enlargements 3 constituting inner and outer rail braces for the base flanges 65 4 of a rail 5. The rail 5 has that portion thereof which is mounted upon the plate 1 provided with transverse serrations, corrugations or ribs 6 which are adapted to engage in a complementary surface 7 provided 70 therefor upon the plate 1, between the enlargements 3.

The plate 1, at the enlargements 3 has openings 8 for spikes or other fastening means employed for retaining the plate 75 upon a tie or other support.

In the construction of the track, it is preferable to arrange the plates 1 of the rails so that the vertexes of the ribs 2 will confront, consequently any spreading action 80 of the rails of a track will simply tend to tighten the plates 1 relatively to the rails thereof.

One embodiment of the invention has been illustrated but it is to be understood 85 that the structural elements are susceptible to such variations and modifications as fall within the scope of the appended claim.

What I claim is:

A rail chair comprising the combination 90 with a rail having the lower face of its base flanges provided with transversely extending serrations, of a rectangular rail supporting plate provided with spaced transversely extending enlargements engaging 95 the edges of the base flange of a rail to prevent lateral shifting of the latter, said plate having its upper face, between said enlargements, formed with longitudinally extending serrations alternately disposed with 100 respect to the serrations on the base of the rail, the serrations in the plate engaging in the serrations of the base to prevent longitudinal movement of the rail, said plate provided with diagonally disposed openings 105 for the passage of spikes, and longitudinally converging ribs integral with the lower face of said plate and V-shaped in

cross section, said ribs merging into each other at their outer ends centrally of the lower face of the plate, one of said openings arranged between said ribs and the other of said openings arranged at the outer side of one of the ribs and near the outer end of the latter.

In testimony whereof I affix my signature in the presence of two witnesses.

JOHN RAYMAN JENNINGS.
